UNITED STATES PATENT OFFICE

108,840

DESIGN FOR A FRAME FOR A GARMENT PRESSING MACHINE

William Strobridge, Syracuse, N. Y., assignor to
United States Hoffman Machinery Corporation,
New York, N. Y., a corporation of Delaware

Application December 28, 1937, Serial No. 73,904

Term of patent 7 years

To all whom it may concern:

Be it known that I, William Strobridge, a citizen of the United States, residing at Syracuse, in the county of Onondaga and State of New York, have invented a new, original, and ornamental Design for a Frame for a Garment Pressing Machine, of which the following is a specification, reference being had to the accompanying drawing, forming part thereof.

The figure is a perspective view of a frame for a garment pressing machine seen from the forward portion thereof, showing my new design, both sides of the frame being the same.

I claim:

The ornamental design for a frame for a garment pressing machine, as shown and described.

WILLIAM STROBRIDGE.
